(57) **CLAIM**

The ornamental design for a surface mount connector of indeterminate length, as shown and described.

DESCRIPTION

FIG. 1 is a perspective view of a surface mount connector of indeterminate length according to the present invention; FIG. 2 is a left end view of the design shown in FIG. 1; FIG. 3 is a right end view of the design shown in FIG. 1; FIG. 4 is a top view of the design shown in FIG. 1; FIG. 5 is a side view of the design shown in FIG. 1, the opposite side of which is a mirror image; and, FIG. 6 is a bottom view of the design shown in FIG. 1.
